Inventor

George S. Hart

4. May Lindsey,
His Attorney

UNITED STATES PATENT OFFICE.

GEORGE HEGERMAN HART, OF WEST HARTFORD, CONNECTICUT.

ELECTRIC SWITCH.

Application filed March 3, 1923. Serial No. 622,559.

To all whom it may concern:

Be it known that I, GEORGE H. HART, a citizen of the United States, and a resident of West Hartford, county of Hartford, and State of Connecticut, have invented certain new and useful Improvements in Electric Switches, of which the following is a specification.

This invention relates generally to electric switches of the type having a rotary handle which may constitute a pointer to indicate the indexed positions of a switch unit, the latter having a suitable blade or blades adapted to be thrown with a quick movement into and out of engagement with suitable terminals fixed on a base.

For many reasons it is preferable that the handle be made of porcelain, or of a material of similar characteristics, but heretofore the objection to porcelain handles has been that porcelain cannot be molded to close dimensions thus making it necessary to allow a relatively large tolerance in those portions of the handle which engage those members through which the switch unit is thrown when the handle is rotated. This has meant that the handles could not be made with sufficient accuracy to eliminate looseness between the handles and the parts to which they are connected or associated, and the result has been that the handles would wobble and vary in their indicating positions.

The aim of the present invention is to provide an improved arrangement having various features of novelty and advantage, and more particularly to provide certain improvements in switches of this sort whereby looseness between the handle and the parts associated therewith is practically eliminated and the handle will stand in close indicating positions; that is to say, it will point within relatively close limits to the indicia signifying the "off", "on", etc., positions of the switch unit.

The above and other objects of the invention are obtained in the structure described in the following specification and illustrated in the accompanying drawings, it being understood that the present disclosure is by way of exemplification only and that the invention is susceptible of various modifications and changes which are within the spirit of the invention without departing from the scope of the appended claims.

In said drawings—

Figure 1 is a plan view of the switch, this switch being shown by way of illustration only, and more or less diagrammatically, as it is obvious that the novel features of the invention may be incorporated in switches differing in construction from that here shown;

Fig. 2 is an exploded view showing, in perspective, the switch handle and certain parts to be connected thereto;

Fig. 3 is a central sectional view through the handle;

Fig. 4 is a view of the handle in side elevation, the pointer end thereof being in section; and

Fig. 5 is a bottom plan view of the handle.

In these drawings I have shown so much of a switch of the type illustrated in the patent to Smart and Gates, No. 1,409,146, dated March 7, 1922, as is necessary to make clear one application of the present invention.

10 is a base of insulating material and of any desired shape, on which are fixed terminals 11, suitably spaced apart, say at 90 degrees, as shown. Journaled in the base is a spindle 12 with which is associated a switch unit, having a blade or blades, which is not shown as the same forms no particular part of the present invention. Secured to the spindle is a U-shaped spring plate 13 having an upwardly extending projection or tongue 14 adapted to be operatively connected to the handle 15, as hereinafter described more in detail. Loose on the spindle and positioned about the spring plate is, what may be termed for convenience, an abutment 17 which is secured to the switching unit. Coiled about the spindle and having its ends straddling the spring plate and the abutment is a spring 18. In operation the handle may be turned step by step in either direction to effect the desired electrical connection between the contacts or terminals. When the handle is thus turned the spring is placed under tension until a certain part of the switching unit is released and then the spring throws the switching unit with a quick movement. The handle 15, which is preferably of porcelain, is provided with a bore or well 20 having longitudinally extending grooves 21 which receive the guides or wings 22 of a connector or sleeve 23 internally threaded so as to re-

ceive the upper threaded end of the switch spindle. The handle is normally held against longitudinal movement relative to the sleeve by a spring 24 abutting against a collar 25 loosely receiving the sleeve and held in place by a spring 26 sprung into an annular groove in the wall of the bore adjacent its open end.

For the purpose of connecting handles of identical construction to switch spindles in various angular positions corresponding to the angular position of the respective switches on the bases,—thus making it possible to meet, from a single stock of handles, the requirement that the handles of the several switches extend in the desired directions in their indexed positions,—the handle is provided with a plurality of notches 30, 30^a, 30^b,—adapted to receive the projection 14 and spaced apart in accordance with the angular position of the various switches on their bases, and a plurality of washers for selectively blanking all but one of the notches are provided, all as is disclosed and claimed in the co-pending application for Letters Patent of Frederic P. Gates, Serial No. 555,997, filed April 22, 1922. The numeral 31 designates one of said washers, this washer blanking notches 30^a and 30^b, and having an aperture 32 adapted to register with notch 30. It will be understood from the foregoing that there are provided a second washer (not shown) similar to washer 31, but having an aperture 32^a (as shown by dotted lines in Fig. 5) adapted to register with notch 30^a; and a third washer having an aperture 32^b registering with notch 30^b. Each washer is provided with a pair of openings 33 through which the arms 34 on the collar 35 extend for the purpose of securing the washer in place.

As previously stated, handles of porcelain or like material having similar characteristics, cannot be made to exact dimensions, and handles of this sort though formed in the same mold, will vary. This means that the well 20 and the notch 30 (where one notch is provided, or notches, where a plurality are provided to accomplish the objects set forth in the said Frederic P. Gates application) must be made oversize, and, therefore, the connector and the projection 14 fit more or less loosely; and where the engagement between the walls of a notch in the handle and the projection is relied upon to hold the handle against rotation relative to the spindle, there is so much play between the parts that the handle will wobble and will not take indicating positions with precision. In order to eliminate these objections I provide on the bottom of the handle, a plate, and anchor this plate against relative turning movement to the handle at a point beyond the projection, the plate having a notch or notches, as the case may be, for closely receiving the pro-

jection. The plate, in the present instance, is in the form of a disc 40 provided with a radially extending arm 41 having its end 42 upturned to engage in a recess or depression 43 positioned in the pointer portion of the handle. This plate, in the present illustration, is shown interposed between the handle and the washer 31, and is provided with apertures 44, 44^a, and 44^b, corresponding to the notches 30, 30^a, and 30^b. These apertures are of such size that the projection 14 will have a close fit therein. Also, the plate has a central aperture in which the sleeve or connector has a relatively close sliding fit. It will be noted that since the projection fits closely in that aperture in the plate which is not covered by the washer, and the plate is anchored against turning movement relative to the handle at a point relatively beyond the spindle, the handle will have little or no loose play and will be held steady to closely indicate the indexed positions of the switch; for instance, when the switch is in "off" position, the pointer end of the handle will be aligned with the middle letter "F", as shown in Figure 1.

What I claim is:—

1. In an electric switch and in combination, a rotary switch spindle having a projection offset therefrom, a handle connected to said spindle, and a plate anchored to said handle at a point beyond said projection and having engagement with said projection for preventing relative rotary movement between the handle and spindle. 95
2. In an electric switch, and in combination, a rotary switch member having an offset projection, a handle constituting a pointer, a plate anchored to said handle at a greater distance from said spindle than said projection and having an aperture adapted to receive said projection. 105
3. In an electric switch and in combination, a rotary switch spindle provided with an offset projection, a porcelain handle, means for securing said handle against withdrawal from the spindle while permitting rotary movement therebetween, and a metallic plate anchored to said handle at a point beyond said projection and having an aperture closely receiving said projection. 110
4. In an electric switch and in combination, a rotary switch spindle having an offset projection, a handle, means within the handle for engaging said spindle, and a plate on the bottom of said handle recessed to receive said projection, and having an arm anchored in said handle to hold the plate and handle against relative rotation. 120
5. In an electric switch and in combination, a rotary switch spindle having an offset projection, a handle having a bore, a connector slidably mounted in said bore and held against rotation relative to said handle 130

and adapted to be threaded onto said spindle, a spring normally urging the handle against longitudinal movement relative to said connector, and a plate on the bottom of said handle having an opening slidably receiving said connector and an aperture adapted to closely receive said projection, said plate having a radially extending arm with an upturned end projecting into said handle.

6. In an electric switch and in combination, a rotary switch spindle having a fixed projection, a handle provided with a plu-

rality of angularly spaced recesses adapted to receive said projection, means for connecting said handle for sliding and rotary movements to said spindle, a plate on the bottom of said handle having apertures registering with said notches, said plate being anchored to said handle at a point beyond said projection, a washer overlying said plate having a single aperture adapted to register with one of said apertures in said plate, and common means for securing said washer and said plate to said handle.

GEORGE HEGEMAN HART.
